UNITED STATES PATENT OFFICE.

DAVID L. AINSLEY, OF MAMMOTH, PENNSYLVANIA.

BRAKE.

1,222,347.

Specification of Letters Patent. Patented Apr. 10, 1917.

Application filed October 14, 1916. Serial No. 125,694.

To all whom it may concern:

Be it known that I, DAVID L. AINSLEY, a citizen of the United States, residing at Mammoth, in the county of Westmoreland 5 and State of Pennsylvania, have invented certain new and useful Improvements in Brakes, of which the following is a specification, reference being had to the accompanying drawings.

10 This invention relates to certain improvements in brakes and has relation more particularly to a device of this general character especially designed and adapted for use in connection with mine cars or other cars 15 of a similar type; and it is an object of the invention to provide a novel and improved brake operating in an automatic manner for preventing the backward travel of a car in the event a coupling between two of the cars 20 or at any point in the train of cars should be broken.

Furthermore it is an object of the invention to provide a novel and improved brake of this general character including a dog 25 constituting a part of a coupling which, in the event of the coacting cars becoming separated or the train breaking at any point, will rock by gravity and coact with the trackway to prevent backward movement of 30 the car or cars.

The invention consists in the details of construction and in the combination and arrangement of the several parts of my improved brake whereby certain important 35 advantages are attained and the device is rendered simpler, less expensive and otherwise more convenient and advantageous for use, all as will be hereinafter more fully set forth.

40 The novel features of the invention will hereinafter be definitely claimed.

In order that my invention may be the better understood, I will now proceed to describe the same with reference to the accompanying drawings, wherein—

Figure 1 is an elevational view illustrating a brake constructed in accordance with an embodiment of my invention; and

50 Fig. 2 is a view in perspective of the dog included in my improved brake, certain of the parts coacting therewith being indicated by dotted lines.

As disclosed in the accompanying drawings, C—C denote adjacent cars of a train

and preferably comprising the rear or tail 55 end of a train.

B denotes a brake dog substantially in the form of an L with the foot portion 1 thereof substantially vertically disposed when said dog is in normal position with the stem portion 2 thereof directed on a predetermined longitudinal curvature and which contacts with the under surface of the body of the rear car as is believed to be clearly disclosed in the accompanying drawings. 60

The portion 1 of the dog B is provided with the longitudinally spaced openings 3 through which are disposed the links 4 and 5 extending in opposite directions. The forwardly disposed link 4 is adapted to be connected to the coupling A of the forward car through the medium of the draw pin 6, while the rearwardly disposed link 5 is engaged with the clevis 7 coupled to the draw bar D of the rear car through the medium 75 of the pin 8. It will be understood that if the requirements of practice so necessitate the links 4 and 5 may be each connected with a coupling A carried by both of the cars C or if preferred each of said links may 80 have coacting therewith a clevis engaged directly with a draw bar.

In practice it will be evident that should the cars C—C be separated or the train broken at any point in advance of said cars, 85 the brake dog B will overbalance and drop downwardly to the position indicated by dotted lines in Fig. 1 and coact with the track bed to hold the rear car C or the separated portion of the train against backward 90 travel and which is of especial import when the train is being drawn up an incline as generally employed in mines or on inclines of any description.

From the foregoing description, it is 95 thought to be obvious that a brake constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and 100 for this reason I do not wish to be understood as limiting myself to the precise arrangement and formation of the several 105

parts herein shown in carrying out my invention in practice.

I claim:

1. In combination with adjacent cars, a
5 brake dog interposed between said cars and substantially in the form of an L with the foot portion thereof upwardly directed, and means pivotally engaged with the foot of the dog at longitudinally spaced points 10 adapted to be coupled to the adjacent cars.
2. In combination with adjacent cars, a
15 brake dog interposed between said cars and substantially in the form of an L with the foot portion thereof upwardly directed, and means pivotally engaged with the foot of the dog at longitudinally spaced points 15 adapted to be coupled to the adjacent cars, the stem of the brake dog being rearwardly

disposed and adapted to contact with the lower structure of the rear car when the 20 same is in normal position.

3. In combination with adjacent cars, a
25 brake dog substantially L-shaped in form, the foot thereof being upwardly directed and the stem rearwardly disposed and of a length to extend beneath the body of the rear car, links pivotally engaged with the foot of the dog at longitudinally spaced points, said links being oppositely directed and adapted to be coupled to the car. 30

In testimony whereof I hereunto affix my signature in the presence of two witnesses.

D. L. AINSLEY.

Witnesses:

DOROTHY M. AINSLEY,

ANDREW T. AINSLEY.
